(Cl. D86—10)

To all whom it may concern:

Be it known that I, William Taylor Jones, a citizen of the United States, residing at 440 S. Main Avenue, Scranton, in the county of Lackawanna and State of Pennsylvania, have invented a certain new, original, and ornamental Design for a Manicure Stand, of which the following is a specification, reference being had to the accompanying drawing, forming part thereof.

I claim:

The ornamental design for a manicure stand, as shown.

WILLIAM TAYLOR JONES.
